A. ST. C. GARMAN.
PHONOGRAPH STOP AND STARTER.
APPLICATION FILED DEC. 22, 1913.

1,121,345.

Patented Dec. 15, 1914.

UNITED STATES PATENT OFFICE

ADRIAN ST. C. GARMAN, OF PHILADELPHIA, PENNSYLVANIA.

PHONOGRAPH STOP AND STARTER.

1,121,345.

Specification of Letters Patent. Patented Dec. 15, 1914.

Application filed December 22, 1913. Serial No. 808,121.

To all whom it may concern:

Be it known that I, ADRIAN ST. C. GARMAN, a citizen of the United States, residing in the city and county of Philadelphia, 5 State of Pennsylvania, have invented a new and useful Phonograph Stop and Starter, of which the following is a specification.

My invention has for its object the automatic stopping of the support of the record 10 of a talking machine when the end of a record is reached, whereby such stopping will be instantly and positively effected, and the defacing of the record and the production of objectionable sounds will be prevented.

The invention consists of novel means for adjusting the device relatively to the extent of movement of the reproducer supporting arm of the machine, whereby the brake of 20 the device will operate with promptness and precision on the record support.

It consists also of novel means for moving the brake-operating member of the device.

It consists also of novel details of construction.

The invention is satisfactorily illustrated in the accompanying drawing, but the important instrumentalities thereof may be varied, and so it is to be understood that the 30 invention is not limited to the specific details shown and described.

Figure 1 represents a top or plan view of an automatic stopping attachment to sound producing and speaking machines embodying my invention. Fig. 2 represents a side elevation thereof on an enlarged scale. Fig. 3 represents a longitudinal vertical section thereof. Fig. 4 represents a horizontal section of a portion on line $x-x$ Fig. 2. Fig. 5 40 represents a transverse vertical section on line $y-y$ Fig. 3.

Similar numerals of reference indicate corresponding parts in the figures.

Referring to the drawings:—1 designates 45 a box or casing on a side of which is a chamber 2 within which is the brake shoe 3, the latter being mounted eccentrically by the vertically extending pin 4 on the upper wall of said opening and base 5 of the casing,

whereby said shoe may move out from the 50 side of said casing and return into said opening, the back 6 of said shoe being circular or bulging for a purpose to be hereinafter explained. The casing 1 is adapted to be placed on and secured to the table, 55 cabinet or box of the machine adjacent to the periphery of the record-support or turntable, say as in Fig. 1.

On the casing are mounted the heads 7 and 8 which are adapted to slide thereon in 60 the direction of the length thereof, said heads being separable from each other. Depending from and secured to the head 7 is the tongue 9 which freely occupies the longitudinally-extending passage or opening 10 65 in the casing 1, so as to be movable in said passage while it is movable with said head 7. The head 8 rests on said tongue 9 and is connected therewith by a friction joint which is composed of the spring or spring 70 plate 11 which bears against the underside of the upper wall 12 of said tongue and is connected with the head 8 by the screws 13 which pass through said spring and freely occupy and are adapted to ride in the longitudinally extending passage or channel 14 75 in said wall 12, and from whence they enter said head and so are secured thereto, whereby when superior force is applied to the head 8, it may be moved on the tongue sliding 80 thereon, thus adapting the said head to be adjusted to and from the head 7, but under ordinary circumstances the friction joint couples said head 8 with said tongue whereby said tongue and head may move as one. 85

Rising from the head 7 is the pin or post 15, and rising from the head 8 is the pin or post 16. The front end of the tongue 9 is cut away forming the incline or slope 9* which when said tongue is advanced is 90 adapted to contact with the back 6 of the brake shoe 3 to throw out the latter.

Interposed between the bottom of the tongue 9 and the base 5 is the washer plate 17, which is secured to the underside of said tongue and abuts or bears freely against the shoulder 18 on the interior of a side of the casing 1, thus serving to prevent rising of

said tongue in the casing, and consequently of the heads 7 and 8 from the top of said casing.

The operation is as follows:—The head 8 is separated from the head 7 relatively to the adjustment required for the throw of the arm 19 of the machine. Then the side of said arm is placed against the post 15 and then when it starts it describes its motion, 10 usual in the class of machines in question. It then reaches the pin 16 causing the head 8 to traverse to the left and with it the tongue 9 whereby the latter reaches the brake shoe 3 when its slope 9* bears against the back 6 of the same as a cam, thus forcing out the shoe and pressing it firmly against the record support, this being at the instant of the end of the throw of said arm when the record has completed its work, and so 20 positively stopping said support that the needle or the sound producing device 20 is prevented from scratching or marring the record, or causing objectionable sounds by said device. The arm may then be moved to 25 the right, whereby its side will contact with the post 15 and so restore the head 15 to its normal position, and with it the head 8, and the tongue 9, without disturbing the adjustment of the head 8, the brake shoe being 30 released of the tongue and free to move into the chamber 2 and so clear of the record support. When a new record is applied, the arm is again placed against the post 16 and the machine started when the operation of 35 the attachment repeats.

Having thus described my invention what I claim as new and desire to secure by Letters Patent, is:—

1. In a stopping device of the character 40 stated for a talking machine, a brake shoe, a plurality of movable heads, having means between which the tone arm is received, and a member on said heads for operating said shoe, one of said heads being adjustably 45 mounted on said member, and adapted to move with it said member and the other head as one.

2. In a stopping device of the character 50 stated for a talking machine, a casing, a brake shoe, a support having means between which the tone arm is received therefor, a plurality of heads on said support, a member on said support adapted to operatively engage said shoe, the same being attached to 55 one of said heads, and to be frictionally connected with the other head, adapting the last named head to be adjusted relatively to a movable member of said machine.

3. In a stopping device of the character 60 stated for a talking machine, a brake shoe thereon, a slidable member in said casing adapted to engage said shoe, and a plurality of heads on said casing having means between which the tone arm is received, one 65 head being fixed to said member, and the

other head being movably connected with the same adapting the latter named head to be adjusted relatively to a movable member of the machine which is adapted to engage said adjustable head.

4. In a stopping device of the character 70 stated for a talking machine, a casing, a plurality of heads thereon adjustably separated and having means between which the tone arm is received, a tongue attached to 75 one of said heads and adjustably connected with the other head by a friction joint, and a brake shoe on said casing adapted to be engaged by said tongue and forced out by the same, said last named head being adapted to 80 be engaged by a movable member of said machine.

5. In a stopping device of the character 85 stated for a talking machine, a casing, a movable tongue therein, a brake shoe on said 90 casing adapted to be engaged by said tongue, a head on said casing attached to said tongue, an auxiliary head on said head, a friction joint connecting said auxiliary head with said tongue, and means on said auxiliary 95 head for the engagement of a movable member of said machine therewith.

6. In a stopping device of the character 100 stated for a talking machine, a casing, a brake shoe thereon, a slidable member in 105 said casing adapted to operatively engage said shoe, and a plurality of heads on said casing being fixed to said member, and the other head being movably connected with the latter by a friction joint, adapting the heads to be adjusted relatively to a movable member of the machine which is adapted to engage the last named head, adapting said member and plurality of heads to be moved as one.

7. In a stopping device of the character 110 stated for a talking machine, a casing, a brake shoe thereon, a slidable member in 115 said casing adapted to engage said shoe, a head on said casing connected with said member adapted to be engaged by a movable part of said machine, and a washer plate connected with said slidable member and movable therewith, said casing having a shoulder with which said plate freely abuts.

8. In a stopping device of the character 120 stated for a talking machine, a casing, a brake shoe thereon, a slidable member in 125 said casing adapted to engage said shoe, a slidable head on said casing, a resilient member on said slidable member, and a connection for said resilient member with said slidable member, said connection passing from said resilient member freely through a channel in said slidable member and into said head.

9. In a stopping device of the character 130 stated for a talking machine, a casing, an eccentrically mounted brake shoe therein

having a cam face, heads movably mounted on said casing and separable from each other, a tongue depending from one of said heads and freely movable in an opening in the casing and engageable by the other head, means carried by said heads between which a movable member of the machine is dis-

posed, and a friction joint connecting the last-named head with said tongue.
